UNITED STATES PATENT OFFICE.

WILLIAM SEARS WHITE, OF DENVER, COLORADO, ASSIGNOR TO THE WHITE FLUSHING VALVE MFG. CO., OF DENVER, COLORADO, A CORPORATION OF COLORADO.

FLUSHING-VALVE.

1,311,365.

Specification of Letters Patent. Patented July 29, 1919.

Application filed June 25, 1918. Serial No. 241,789.

To all whom it may concern:

Be it known that I, WILLIAM SEARS WHITE, a citizen of the United States, and a resident of Denver, in the county of Denver 5 and State of Colorado, have invented a new and Improved Flushing-Valve, of which the following is a description.

My invention relates to flushing valves and is more particularly designed as an improvement on the flushing valve forming the subject matter of United States Letters Patent No. 1,207,353 granted to me December 5, 1916.

The flushing valve is characterized by a reservoir or container having an inlet and an outlet, communication between which is controlled by a valve, preferably a piston valve. An air chamber is provided preferably directly associated with the reservoir structure 20 and communicates with the top of the reservoir above the piston valve through the medium of a vertical passage. The arrangement is such that in operation of the valve the reservoir will be vented above the valve 25 to permit the flow of water thereinto as the valve opens, and whereby as the valve closes air may pass from the air chamber to the top of the reservoir as the water recedes from the latter. After the closing of the piston 30 valve and the cutting off of the water inlet, the remaining water in and below the air chamber will serve for the refill of the bowl or other fixture.

The present invention relates especially to 35 certain improvements including an annular chamber about the main chamber and receiving the water from the inlet to prevent one-sided pressure; means to choke the outlet with the operation of the main valve, and auxiliary means to create a siphon action in 40 a bowl or other fixture in situations where the water supply is small, all as hereinafter particularly explained.

Reference is to be had to the accompanying drawings forming a part of this specification.

Figure 1 is a transverse vertical section of a flushing valve embodying my invention with the present improvements, the valve being closed;

Fig. 2 is a partial transverse vertical section with the valve raised and the parts otherwise in position for flushing;

Figs. 3, 4 and 5 are sectional plan views

respectively on the lines 3-3, 4-4, and 55 5-5, Fig. 1.

In constructing a practical embodiment of the invention in accordance with the illustrated example, a reservoir or container 10 is provided having a cylinder 10^a, in which 60 a valve 11, preferably a piston valve, is movable. An inlet 12 leads to the interior of the reservoir, and an outlet 13 is provided at the bottom to be connected in practice to a bowl or other fixture. An annular water chamber 65 14 surrounds the cylinder 10^a in the reservoir 10 and receives the water from the inlet 12 to prevent one-sided pressure on the piston 11 and said water chamber communicates with the outlet 13 through a passage 15 70 formed by a depending tubular shell between the said chamber and outlet. At the upper end of the passage 15 is a valve seat 16, and a suitable disk 17 or the like is applied to the bottom of the piston valve 11 and secured by 75 a screw 18 or the like.

In the present embodiment of my invention I provide, for unseating the valve, a trip finger 19, said finger being pivoted on a rockable choke plate 20 mounted on a 80 shaft 21, the said plate being connected with a rock shaft 22 through the medium of a sleeve 23 on said shaft having on arm 24 connected by a link 25 with the said rockable choke plate.

An annular air chamber 26 is produced between the tubular inner shell 15 and the main shell of the reservoir 10, and communication between said chamber and said reservoir above the piston 11, is established as 90 follows: A vertical air passage 27 communicates at its lower end with the air chamber 26 and communicates through a port 28 and valve chamber 29 with an auxiliary chamber 30 above the cylinder 10^a, and connects with 95 the latter through a tubular neck 31. The valve 32 controls the port 28 and has a depending stem 33 extending into the vertical passage 27. Also, a valve 34 seats on the upper end of the neck 31 and controls communication between the auxiliary chamber 30 and the cylinder 10^a. An extension sleeve 35 is slidable on the neck 31 and normally gravitates to a position directly below said neck to be engaged by a valve 36 on the 100 piston 11. To open the valve 32 simultaneously with the raising of the piston valve 11, a bar 37 is disposed in the by-pass 27 and its

upper end is directly adjacent the stem 33 on the valve 32, while the lower end of said bar 37 rests on a rocker arm 38 on the shaft 22. The rock shaft 22 may be operated in any 5 suitable manner, there being indicated a handle 39 for the purpose.

In practice when the piston valve 11 is in the closed position, the chamber 26 is filled with air. When the handle 39 is raised the 10 auxiliary valve 32 and the piston valve 11 will both be raised from their seats. At the same time the disk 20 will be swung horizontally to partly close the passage 15, causing the water from inlet 12 to follow upward 15 into the cylinder 10^a, and through the neck 31, chambers 30 and 29, and port 28, and downward through the passage 27 and outlet 13 to the bowl, it being understood that the piston valve 11 has not a tight-fit in the 20 cylinder 10^a, but permits the flow of a limited quantity of water around said piston valve and to the chamber 30. The upward passage of the water in the cylinder 10 carries the piston or equivalent valve 11 upwardly 25 to the top of the cylinder 10^a. The ascent of the piston is very rapid and if allowed to continue unchecked until it strikes the top of the cylinder 10^a will produce a disagreeable noise. The sliding sleeve 35 prevents the 30 free movement of water into the chamber 30 after the valve 36 engages and closes the bottom of the neck 31, but it permits the piston valve 11 and sleeve 35 to ascend slowly after engagement of said sleeve with 35 the valve 36 and the water cushion is displaced. When the handle or lever 39 is released the passage 15 is opened and the valve 32 allowed to seat. The water now will flow from the inlet 12 and the annular chamber 40 14 directly through the passage 15 to the outlet 13. The passage 15 being larger than the outlet 13, and the inlet 12, allows free movement of water through said passage which chokes the smaller mouth of the outlet 45 13. This causes a pressure below the body of air in the chamber 26 which is almost, if not quite, equal to the pressure in the cylinder 10^a and chamber 30, and causes the air to pass from the air chamber 26 50 through the passage 27, causing the check valve 32 to lift, so that the air passes through the valve chamber 29, to the chamber 30. The valve 34 has guided movement in a stem 34^a threaded into the top of the chamber 30 as at 34^b, whereby to regulate the opening between the valve 34 and its seat 34^c so that the period of flushing can be regulated by controlling the passage of air 55 from the chamber 30 to the cylinder 10^a above the piston valve 11.

In connection with the rock shaft 22, I employ a substitute for a stuffing box, whereby to prevent the tightening of the packing nut 40 to a degree to cause the shaft 60 to be bound. For the purpose a rubber

sleeve 41, which, initially, is of the general form of a nipple of a nursing bottle, is placed on the shaft, and fitting on the shaft within the sleeve 41 is a flanged collar 42. The flanged collar 42 and the corresponding 70 flange 43 on sleeve 41 are clamped between the nut 40 and the adjacent threaded boss 40^a on the reservoir 10 through which the shaft 22 passes. The rubber sleeve 41 has an expanded zone 41^a near the inner end so 75 that the extreme inner end tightly hugs the shaft to give a tight joint, while at the same time the nut 40 will securely clamp the said sleeve 41 and the collar 42 in position and will prevent the nut from binding 80 against the usual collar or flange 44 on the shaft.

In situations where the water supply is small and where it is necessary to furnish a volume sufficient to create a siphon action in 85 a bowl or other fixture, an auxiliary pipe 49 may be employed communicating with a pressure tank 50 and communicating with both the main supply pipe 52 and inlet pipe 12 of the reservoir. When this attachment 90 is employed the auxiliary chamber 30 communicates by a recess 45, a port 46, a coupling section 47, and pipe 48 with the said auxiliary pipe 49. The port 46 is controlled by a ball valve 51 or the like in the 95 coupling section 47. It is a well known fact that it is practically impossible to keep the necessary air in a pressure tank or pipe; therefore the replenishing of the air from time to time is required. With the arrangement shown, it is possible to supply a body 100 of air to the auxiliary pipe 49 at every operation of the flushing valve. This is so because the air which has passed from the air chamber 26, to chamber 30, while the 105 flushing valve is in operation, will find its way through the pipe 48 and its connections with said chamber 30 to the auxiliary pipe 49 after the piston valve 11 is seated. The ball 51 being forced against 110 its seat prevents too much water returning from the auxiliary pipe 49 through the pipe 48 when the piston valve 11 is open. The coupling 47 affords a ready means of gaining access to the valve 51 and its seat. 115

In the choking of the mouth of the outlet 13 the rising of the water in the air chamber 26 will seal said chamber. This results in the alternate passage of air between the said air chamber and the chamber 30 and 120 cylinder 10^a, and a quantity of water is insured in the air chamber in addition to any water remaining below the same to act as a refill of a bowl after flushing. The construction also results in preventing what is 125 known as a water hammer.

In practice I find that the water from container 14 exerts a suction or pull on piston 11 as said water passes into passage 15 this with the aid of a back pressure due to the 130

water being retarded at flush rim of a bowl or other fixture will produce the same effect that a small opening 13 will do.

Having thus described my invention, I claim as new, and desire to secure by Letters Patent:—

1. In a flushing apparatus, a reservoir adapted to contain flushing water and provided with an inlet, and an outlet, an air chamber in communication with the outlet adapted to be liquid-sealed by the flushing water to cause a quantity of water to be held by the air chamber for the refill of a fixture, and means to direct the air in said chamber 10 to the reservoir at the top of the latter in discharging the reservoir, and for directing air to the air chamber from the reservoir in the filling of the latter; together with a pressure tank, a pressure pipe connecting 15 the pressure tank and with the inlet of the flushing valve, and connections between the said pressure pipe and the reservoir at the top of the latter whereby to renew the air in the pressure tank and pipe from the 20 flushing valve.
2. A flushing valve including a container having a water inlet, a water chamber with which the inlet is in communication, a discharge outlet from which water may flow 25 from the water chamber, a vertically movable valve in the water chamber and controlling
3. A flushing valve including a container 45 having an inlet, and an outlet; a water chamber in communication with the said inlet and outlet, a vertically movable valve in said chamber controlling the inlet, an auxiliary chamber above the water chamber, an air 50 chamber, passages establishing communication between said auxiliary chamber and the air chamber, means controlling communication through said passages, and means establishing communication between the auxiliary 55 chamber and the water chamber, said means including a vertically slidable tubular member at the top of the water chamber, together with a member on the vertically movable valve to engage said vertically slidable 60 member.

WILLIAM SEARS WHITE.
